JACKET CROWN

Abram J. Pearlman, Chicago, Ill.

Application September 5, 1941, Serial No. 409,713

3 Claims. (Cl. 32—12)

The present invention relates to dental processes and particularly to the crowning of teeth. The main object of the invention is to provide a new and improved jacket crown that may be made in stock sizes, shapes, colors, etc. with the proper surface lines and facets to adequately match natural teeth and applied by the dentist without using auxiliary metal linings and the like.

It is also an object of the present invention to improve the process of applying jacket crowns to teeth. This invention enables a dentist to produce an inexpensive and natural reproduction of a normal tooth to replace a badly broken down and decayed tooth, in a simple manner, by selecting a suitable ready made stock crown which can be easily adapted to the remaining tooth stump.

Other detailed objects and advantages of the invention will appear from the following description and the drawing disclosing the preferred form of the invention. It should be understood however that the description and drawing are illustrative only and are not intended to limit the invention except insofar as it is limited by the appended claims.

In the drawing—

Fig. 1 is a labial view of a tooth illustrating generally the preparation of a tooth to be crowned;

Fig. 2 is a view illustrating the measurement of the widest part of the stump preparation;

Fig. 3 is a view illustrating the measurement of a stock jacket crown to determine its adaptability to the prepared tooth stump;

Fig. 4 is a sectional view of the crown element; and

Figs. 5 and 6 are sectional views illustrating the fitting of the selected crown upon the tooth stump.

In order that the nature of my invention may be more clearly understood I will describe one method of preparing and crowning a tooth in connection with the accompanying drawing. The tooth to be crowned, illustrated in Fig. 1, consists of a root portion 10 and an exposed portion 11 (shown only in dotted lines in Fig. 1). The enamel is first removed down substantially to the gingival section and then as much of the dentine is removed as is necessary to form a conical stump without any undercuts. The stump tapers from the gingival line to the end thereof. All of the axial walls and the occlusal or incisal surfaces are reduced so that the gingival section is left as the largest cross section of the tooth. The tapering of the stump is carried right out to the

original surface at the gingival section. The resulting appearance of the prepared tooth is substantially as shown in Fig. 1 of the drawing.

The next step in the preparation of the tooth for crowning consists in measuring the circumference and shape of the prepared tooth stump 12. As illustrated in Fig. 2, a wire loop 13 is applied to the stump 12, the loop being fixed in a dentimeter or ordinary broach holder 14. The wire loop 13 is tightened until the wire engages loosely with the root surfaces of the tooth. The wire loop is then carefully adjusted so that it is even with or slightly under the gum margin at the widest section of the tooth, and is then twisted tight about the widest section. The wire is then carefully removed so as to retain the circumferential shape of the tooth stump at its widest cross section.

Having made the measurement the dentist is now ready to prepare and attach a crown. The present invention is particularly advantageous in enabling the dentist to provide a proper jacket crown for application to a tooth prepared in the foregoing manner. Heretofore it has generally been the practice for the dentist to take impressions and then make a crown or have someone make a crown to fit a particular stump. Where this has not been the practice stock crowns are used but such stock crowns are of porcelain combined with some other material such as gold or a gold alloy sleeve. Heretofore, so far as I am aware, it has not been possible to directly fit a stock crown upon a tooth stump without the necessity of using either a metal lining and reinforcement for the porcelain.

In accordance with my preferred practice I make the crowns from a material having a certain amount of elasticity, with the necessary Brinell hardness and tensile strength. I have found that the acrylic resins are particularly satisfactory for my purpose although other resins or acrylic resins in combination with other substances having the desired characteristics may also be used. For example, Polystyrene and methacrylate resin are satisfactory. Their Brinell hardness and tensile strength, when properly prepared, compare favorably with the better gold alloys. A plastic of one of these materials may be given a Brinell hardness of 40 to 60 with a tensile strength of 15,000 to 30,000 pounds. These materials are easy to finish and polish, are non-conductors of electricity, and have low thermal conductivity.

The crown itself is preferably molded in quantities of stock shapes, sizes and colors to fit the

space between adjacent teeth and to match the shade of adjacent teeth. By making quantities of stock shapes the dies for molding the crowns may be prepared with sufficient care to reproduce the lines and facets that are found on the surfaces of natural teeth.

In accordance with my invention the dentist, after having prepared the tooth stump and taken the measurement thereof, next selects a stock jacket crown of the type and shade to match the neighboring teeth and of approximate fit as to width and length (preferably a slightly larger all over dimension, selected so as to establish proper contact with the adjacent teeth). The wire loop is placed on the base of the selected crown so that the anatomical form as indicated by the wire loop will remain within the limit of the surface 16 at the open end of the crown 15 (see Figs. 3 and 4). The labial or buccal part of the loop should be placed as close as possible to the external labial or buccal border of the stock crown and in this position the loop is outlined on the surface 16 by etching on the plastic or by means of articulating paper or paste.

The dentist then proceeds to ream out the chamber 17 of the crown to the outline of the loop. Care must be exercised not to extend beyond the border of the outline. The crown material is readily worked down so that it can be seated on the tooth stump with considerable accuracy and brought into proper relation with the adjacent teeth. The dentist of course may use articulating paste to indicate the high spots which should be eliminated in fitting the crown onto the tooth stump. This fitting is illustrated best in Fig. 5 where it will be noted that the inner surface 19 of the crown 15 has been worked down so as to fit the crown snugly upon the tooth stump 12. The external wall 18 of the crown is then reduced around the gingival portion so that no overhang remains below the gum line. That is, the tapering is carried right out to a junction with the tooth surface at the gingival section (see Fig. 6).

Proper contacts are established with the adjacent teeth and the top of the crown is ground in to fit the opposing teeth as to bite and established height. The crown is then polished by slight buffing with a soft wheel and is cemented directly to the tooth stump with a suitable cementing substance.

From the foregoing description it is believed to be clear that I have provided an improvement in the crowning of teeth and in jacket crowns whereby a tooth stump may be crowned with a single material jacket crown that affords a high degree of protection. The crown is particularly

good because of its low heat conductivity, its non-conductivity of electrical currents, and the absence of any metallic linings or other fastening means of metal. The fact that the crown may be tapered to a thin finishing edge at the gingival section of the tooth permits the retention of a heavy base for the tooth stump and eliminates the necessity of providing a shoulder on the tooth stump.

Having thus described my invention, what I claim as new and desire to secure by Letters Patent is:

1. The method of crowning a tapered stump having its greatest cross sectional area at the gingival section meeting the original tooth surface without a shoulder which comprises, providing a tooth simulating jacket crown with a tapered chamber in one end and a relatively wide flat surface around said chamber, marking the contour of the base of the tapered stump on said surface and fastening the crown to said stump so as to cover the entire exposed area of the tooth stump by reaming out the chamber within the crown to the marked contour and cementing the jacket crown directly to the stump.

2. The method of crowning a tapered stump having its greatest cross sectional area at the gingival section meeting the original tooth surface without a shoulder which comprises, providing a tooth simulating jacket crown with a tapered chamber in one end and a relatively wide flat surface around said chamber, marking the contour of the base of the tapered stump on said surface and fastening the crown to said stump so as to cover the entire exposed area of the tooth stump by reaming out the chamber within the crown to the marked contour and cementing the jacket crown directly to the stump, and cutting down the outer surface of the crown to meet the original tooth surface at the gingival section.

3. A jacket crown for direct and permanent application to a tapered tooth stump, said crown having a recess extending into it from one end, the crown having its outer surface formed to simulate a natural tooth, said crown being composed of high tensile strength resin material of low heat conductivity, substantially a non-conductor of electricity and non-frangible, said crown having a thick wall terminating in a flat surface about the open end of the recess sufficient to encompass, between the recess and the outer periphery, normal variations in size and shape of tooth stumps, whereby the crown recess may be enlarged to fit a stump and the periphery may be cut down to a smooth meeting with the original tooth surface at the gingival section.

ABRAM J. PEARLMAN.
